DRIVE TERMINAL PYLON FOR AERIAL TRAMWAYS

Tony R. Sowder, Spokane, Wash., assignor to Riblet
Tramway Company, a corporation of Washington

Application May 15, 1958, Serial No. 50,905

Term of patent 14 years

(Cl. D41—1)

FIG-1

FIG-2

FIG-3

FIG-4

Figure 1 is a rear perspective view of a drive terminal pylon for aerial tramways, showing my new design;

Figure 2 is an enlarged side elevation thereof;

Figure 3 is a fragmentary enlarged top view thereof; and

Figure 4 is an enlarged fragmentary front elevation.

Portions are shown broken away or omitted in Figures 2, 3, and 4 for convenience of illustration. The dominant features of my design reside in the portions shown in full lines.

I claim:

The ornamental design for a drive terminal pylon for aerial tramways, as shown and described.
